2 Claims 10

ABSTRACT OF THE DISCLOSURE

This invention relates to fluorescent brightening agents selected from the group consisting of the free acid and salts of the disulfonic acid of the formula:

15

wherein R represents a member of the group consisting of hydrogen and chlorine. These fluorescent brightening agents which are characterized by a 4-anilino or 3,4-anilino substituent in each of the 4- and 6-positions of the triazine rings are characterized by a high degree of stability to hypochlorite bleach, which is frequently used in laundering.

35

incorporated in a detergent are effective only on cotton, etc. but ineffective on synthetics.

It is therefore an object of this invention to provide a process and composition for whitening both cotton and synthetic goods.

We have discovered that certain 4,4'-bis[4,6-(chloroanilino)-2-triazin-2-ylamino]-2,2'-stilbenedisulfonic acids of the formula:

40

wherein w, x, y and z are 1 or 2, and M is a cation, e.g., H, alkali metal (Na, K, Li, etc.) alkaline earth metal (Ca, Si, Mg, etc.), NH4 or hydroxyalkyl amino

45

($\text{---N}(\text{---CH}_2\text{---CH}_2\text{OH})_w\text{---N}(\text{---CH}_2\text{---CH}_2\text{OH})_z\text{---N}(\text{---CH}_2\text{---CH}_2\text{OH})_x\text{---}$)

2

The use of fluorescent brightening or whitening agents (hereinafter referred to as brightening agents) to brighten and whiten textiles, paper and the like is well known in the art. The usual fluorescent brightening agent is a substantially colorless compound which however has a bluish fluorescence under ultraviolet light so that the bluish fluorescence of the agent will neutralize any yellowness of the fibrous material with which it is used and make it appear whiter or brighter.

One of the largest uses of such brightening agents is in laundering of textiles. However, many of the known fluorescent brightening agents are sensitive to hypochlorite bleach which is frequently used in both home and commercial laundries. Also many brightening agents which are effective on cotton or other cellulosic fibers, have little or no effect on wool or synthetic fibers, and thus are relatively ineffective on mixed textiles, and when

This application is a continuation of our copending application Ser. No. 382,364 filed July 13, 1964, now abandoned.

This invention relates to a new and improved process and composition for brightening and whitening fibrous materials.

etc.) dye cotton and nylon when applied from an aqueous detergent or soap bath or a separate bath. They are characterized by a high degree of stability to hypochlorite bleach which is frequently used in laundries.

To prepare these compounds one mol of 4,4'-diamino-2,2'-stilbenedisulfonic acid is reacted with 2 mols of cyanuric chloride in known manner. One mol of this product is then reacted in known manner with 4 mols of mono or dichloro-aniline, e.g., o, m or p-chloroaniline, 2,4-dichloro-, 3,4-dichloro-, 2,5-dichloro-, 2,6-dichloro or 3,5-dichloro-aniline, either stepwise, i.e., one, two, three or four mols at a time, wherein the chloroaniline derivative used in the different steps is the same or different chloroaniline derivative, or, 4 mols of a single chloroaniline derivative or mixture of chloroaniline derivatives can be condensed in one step. This latter procedure is preferably employed, however, when the chloroaniline substituent is to be the same in all positions and only a single chloroaniline derivative is used, as otherwise a mixture of product is obtained.

The pH was kept slightly alkaline to phenolphthalein with 100 cc. of 20% soda ash. It was steam distilled to remove p-chloroaniline, cooled, filtered and washed with water, then dried in an 80° C. air oven. Dry weight=43.5 g., $K_{max}=47.5$.

Application of this brightener to cotton was carried out as follows using a sodium stearate soap wash bath:

A mixture was prepared of 25 cc. of 1.6% soap solution (8% soap on the weight of the fabric), 125 cc. of water and an aliquot of a brightener solution (0.08% brightener o.w.s.) prepared by dissolving the brightening agent with a $K_{max}=37.5$ in 5 mls. of dimethylformamide followed by dilution to a 1 liter with water. After warming to 130° F. 10 mls. of a solution of sodium hypochlorite containing 2 g. of available chlorine per liter was added. After standing 15 min. a 5 g. piece of cotton fabric was added. The washing mixture was agitated at 130° F. for 20 min., the fabric removed, rinsed and air dried at 40° C.

In a similar fashion an equimolecular amount of the brightener free from halogen atoms:

The following examples illustrate the invention:

30

Example 1

Preparation and application of 4,4'-bis[4,6-di(4-chloroanilino)-2-triazin-2-ylamino]-2,2'-stilbenedisulfonic acid of the formula:

was applied to cotton from a soap-hypochlorite bath. The brightness obtained on the cotton was less than half that obtained from the chloro containing brightener above.

35

At 30° C. was dissolved 15 g. of cyanuric chloride in 65 cc. of acetone. The solution was added in a thin stream to a stirring mixture of 20 cc. of water and 100 g. of ice chips. Then at -8° C. to +3° C., there was added 113.5 cc. of a solution of 4,4'-diamino-2,2'-stilbenedisulfonic

45

Preparation and application of 4,4'-bis[4,6-di(3-chloroanilino)-2-triazin-2-ylamino]-2,2'-stilbenedisulfonic acid:

acid (.04 mol). The pH was kept neutral to congo paper by the addition of 25 cc. of 20% soda ash solution. It was stirred 1 hour at 0° C. to negative amine test. Then there was added 11 g. of p-chloroaniline (.08 mol). The material was stirred and temperature was allowed to rise to 25° C. over a 2 hour period keeping pH faintly basic to brilliant yellow paper with 25 cc. of 20% sodium hydroxide. The mixture was filtered cold and the precipitate was transferred to a 1 liter flask. There was added 75 g.

60

This compound is prepared in the same manner as the compound of Example 1 using an equimolecular amount of m-chloroaniline in place of the p-chloroaniline of Example 1.

On application to cotton in the manner of the compound of Example 1, this brightener gave slightly lower brightness than the tetrachloro brightener of Example 1 65 and definitely higher brightness than the brightener:

of p-chloroaniline and 25 mls of water. The mixture was stirred 1 hour at 60° C., then 24 hours at 95°-100° C.

75 applied at equimolecular concentration.

Example 3

Preparation and application of 4,4'-bis[4,6-di(3,4-dichloroanilino)-s-triazin-2-ylamino]-2,2'-stilbenedisulfonic acid:

This compound is made in the same manner as the compound of Example 1 substituting an equimolecular amount of 3,4-dichloroaniline for the p-chloroaniline used in Example 1.

tered, washed with water, then dried in an 80° C. air oven to give the brightener of the formula first given in this example.

This brightener was applied to nylon cloth (5 g.) by

the method described in Example 1 (omitting the addition of sodium hypochlorite). It gives a visible whitening to nylon under these conditions, at least equal to the whitening effect obtained from:

Application to cotton in the presence of sodium hypochlorite bleach gave similar brightness to the compound of Example 1.

Example 4

Preparation and application to nylon of 4,4'-bis[4-(p-chloroanilino)-6-(3,4-dichloroanilino)-s-triazin-2-ylamino]-2,2'-stilbenedisulfonic acid:

At 30° C. was dissolved 15 g. of cyanuric chloride in 65 cc. of acetone. The solution was added in a thin stream to a stirring mixture of 20 cc. of water and 100 g. of ice chips. Then at -8° C. to +3° C., there was added 113.5 cc. of a solution of 4,4'-diamino-2,2'-stilbenedisulfonic acid (.04 mol). The pH was kept neutral to congo paper by the addition of 25 cc. of 20% soda ash solution. It was stirred 1 hour at 0° C. to a negative amine test. Then there was added 11 g. of p-chloroaniline (.08 mol). The material was stirred and temperature was allowed to rise to 25° C. over a 2-hour period keeping the pH faintly basic to brilliant yellow paper with 25 cc. of 20% sodium hydroxide. The mixture was filtered cold. The compound obtained at this stage is of the formula:

(Tide) on the weight of the fiber. Again sodium hypochlorite was used as in Example 1. Again the whitening effect was distinctly greater on cotton than the whitening effect obtained with the nonchlorinated 4,4'-bis(4,6-dianilino-s-triazin-2-ylamino)-2,2'-stilbenedisulfonic acid.

As indicated by the above examples, the novel brightening agents of this invention are usually used in the form of their sodium salts, however, other alkali metal salts are equally effective and may be obtained in analogous manner by using other alkali metal carbonates or hydroxide (e.g., potassium carbonate and hydroxide) in place of the soda ash and NaOH used in the examples. The free acid of brightening agent may be obtained by acidification with

This precipitate was transferred to a 1 liter flask. There was added 75 g. of 3,4-dichloroaniline and 25 mls. of water. The mixture was stirred 1 hour at 60° C., then 24 hours at 95-100° C. The pH was kept slightly alkaline to phenolphthalein with 100 cc. 20% soda ash. It was steam distilled to remove excess 3,4-dichloroaniline, cooled, fil-

70 strong mineral acids such as HCl and H₂SO₄ and other salts may be produced by neutralization of the free acid with the appropriate base to form the desired salts. The alkaline earth metal salts are particularly effective for whitening photographic paper, etc.

75 While for use with textiles the novel fluorescent agents

are advantageously compounded with the detergent used for laundering, it will be understood that they can be equally well applied in a separate bath or added to a

We claim:

1. The fluorescent brightening agent selected from the group consisting of the free acid and salts of the disulfonic acid.

bleach or rinse water, along with softening agents, etc., if desired.

2. The fluorescent brightening agent selected from the group consisting of the free acid and salts of the disulfonic acid.
